UNITED STATES PATENT OFFICE.

WILLIAM E. HOSCHKE, OF NEW YORK, N. Y., ASSIGNOR, BY MESNE ASSIGNMENTS, TO SONORA PHONOGRAPH CORPORATION, A CORPORATION OF NEW YORK.

AUTOMATIC BRAKE FOR PHONOGRAHS.

1,148,477.

Specification of Letters Patent. Patented July 27, 1915.

Application filed April 6, 1911. Serial No. 619,237.

To all whom it may concern:

Be it known that I, WILLIAM E. HOSCHKE, a citizen of the United States, residing in New York, borough of Brooklyn, in the State of New York, have invented certain new and useful Improvements in Automatic Brakes for Phonographs, of which the following is a specification.

This invention relates to that part of a phonograph which concerns the stopping of the record when the stylus has arrived at the end of the sound-producing groove.

The object of this invention is to provide means which will stop the movement of the record when the piece has been completed, which means are set in operation at the completion of the piece by means which move proportionately to the number of rotations of the record.

More particularly the invention consists of mechanism, one member of which is adapted to be placed at a point removed from the record-stopping means or brake, a distance proportionate to the number of turns to be made of the record, so that by setting this member at such point at the beginning of the piece to be performed, the member will, simultaneously with the completion of the piece, arrive at and actuate the brake, whereby the rotation of the record is automatically stopped, obviating thereby the necessity of a person specially going to the phonograph and manually operating the braking means.

In the accompanying drawing,

Figure 1 is a top-view of a phonograph embodying my invention, with parts broken away, Fig. 2 is a vertical section on line 2—2, Fig. 1, Fig. 3 is a vertical section on line 3—3, Fig. 1, and Fig. 4 is a top-view of the phonograph on a reduced scale.

Similar letters of reference indicate corresponding parts.

In the drawing, 10 indicates the top-plate of the phonograph case, which is provided with an opening 11. Through said opening extends a vertical drive-shaft 12, to the upper end of which is secured the record-carrying disk 13, adapted to support the record 14. At its lower portion the drive-shaft is connected to any suitable motor (not shown), for driving the same.

On the shaft 12 is fixed a pinion 15, engaging a gear 16 mounted to rotate on a vertical stud 17 of a supporting-frame 18

within the phonograph-casing. To said gear is secured, on the same axis, a pinion 19, engaging a gear 20 mounted on a vertical stud 21 of the frame 18. Said last-mentioned gear-wheel 20 carries an upwardly-projecting pin 22, adapted when the gear 20 is rotated, to engage successively the teeth of a ratchet-wheel 23 fixed to an arbor 24 mounted at one end in the frame 18 and at the other end in a bracket 25 of the same. Said arbor carries a pinion 26, engaging a gear-wheel 27 supported at its hub on a bracket 28 of the frame 18, and loosely mounted to rotate on a sleeve 29 of said bracket, said sleeve surrounding the shaft 12 and providing a vertical bearing for the same above the supporting-frame 18.

To the gear-wheel 27 is fixed an outwardly-extending tripping pointer 30, which is provided beyond the disk with a point adapted to move over a curved scale 31 secured on the top 10 of the case, and on the completion of its movement, at one end of the scale, to trip the braking means. The brake comprises an angular brake-lever 32 pivoted on the top 10 and carrying at one end a brake-shoe 33 adapted to engage the edge of the record-carrying disk 13, and having at its other end a handle 34, whereby, after braking, the lever may be manually returned against the tension of its operating spring 35 to inoperative position, in which it is held by a trigger 38. The trigger comprises a U-shaped piece of metal, pivoted off its center to a suitable supporting-bracket 36 of the top 10. During rotation of the disk one leg 40 of the U-shaped trigger engages the brake-lever and thereby retains the brake-shoe away from the disk, while the other leg 41 is located in the path of the tripping-arm 30. When the arm 30 strikes the leg 41, the trigger is moved and the leg 40 is lifted away from the brake-lever, in the position shown in dotted lines in Fig. 3, thereby releasing the same and permitting the brake-spring 35 to operate the brake, thus pressing the brake-shoe against the edge of the disk and bringing the same to rest, as indicated in Fig. 4. A stop-pin 44 limits the return movement of the brake, when restoring the same to inoperative position.

Each record is provided with a number, as for instance, the number 350 (Fig. 4) indicating the number on the scale to which

the tripping-pointer is to be set prior to commencing the operation of the phonograph with the respective record.

5 The tripping pointer having been by hand moved to the number on the scale corresponding to the indicated number on the record, and the stylus 50 having been set at the beginning of the groove, the brake is withdrawn by hand and the rotation of the 10 disk commences.

At each revolution of the pin 22 it engages the ratchet 23 and moves the same forward one tooth, thereby rotating the arbor 24, pinion 26 and gear-wheel 27, and 15 imparting to the pointer 30 a step-by-step movement along the arc-shaped scale toward the brake. When the pointer arrives at the brake, it releases the same in the manner before described, whereby the disk 20 is automatically brought to rest at the completion of the performed composition.

When the pointer is in its final position of rest against the brake-lever, as just described, the pin 22 may be in engagement 25 with the ratchet, and it would then be impossible to again move the pointer by hand to a desired point on the scale, as the engagement of the pin with the ratchet teeth would prevent such movement. To over- 30 come this difficulty, the pinion 26, instead of being fixed to the arbor 24, is loose upon the same, but is held by a spring 51 on the arbor in frictional contact with a collar 52 fixed to the arbor, whereby when the pointer 35 is moved for setting the same, the pinion is by the gear 27 turned on the arbor against its frictional engagement with the collar, without rotating the arbor and ratchet-wheel, which are held against rotation by 40 the pin 22. Or, for releasing the pointer so that it may be moved freely over the scale, the brake may be held by the operator away from the disk for a few turns of the latter, until the pin 22 is out of engagement 45 with the ratchet, thereby permitting free rotation of the ratchet and its arbor and pinion and the free movement of the pointer over the scale for setting the same for a record.

50 One embodiment of the invention has been described, but it is obvious that changes may be made in the construction without departing from the spirit of the invention,

which consists, as before stated, in the tripping-pointer and its scale and the brake 55 actuated by the pointer, whereby the number of turns to be made is capable of being controlled at the beginning of the operation, according to the length of the record to be played.

Having thus described my invention, I claim as new and desire to secure by Letters Patent:

1. The combination of a driving shaft, a rotary element, a stationary arc-shaped graduated scale, an automatic brake having a trip disposed adjacent to said scale, said brake being adapted to stop the rotation of said driving shaft when said trip is released, a pointer arm adapted to move 65 over said scale and engage said trip to release it, and intermediate mechanism between said arm and driving shaft for imparting an intermittent step by step motion to said arm.

2. The combination of a rotary element, a stationary graduated scale, an automatic brake for said rotary element having a trip, a pointer arm adapted to move in relation to said scale and engage said trip to release 80 it, and intermediate mechanism between said arm and rotary element for imparting an intermittent step by step motion to said arm.

3. The combination of a rotary element, 85 a stationary arc-shaped graduated scale, an automatic brake for said rotary element comprising a spring actuated brake lever adapted to engage said rotary element and a U-shaped trigger pivoted off its center and 90 having one leg thereof adapted to engage said brake lever, a tripping pointer arm adapted to move over said scale and engage the other leg of said trigger to permit the operation of the brake, and intermediate 95 mechanism between said arm and rotary element for imparting an intermittent step by step motion to said arm.

In testimony, that I claim the foregoing as my invention, I have signed my name in 100 presence of two subscribing witnesses.

WILLIAM E. HOSCHKE.
